HIRAM B. MORRISON, OF LE ROY, NEW YORK.

Letters Patent No. 79,493, dated June 30, 1868.

IMPROVEMENT IN REVOLVING HOSE-NOZZLES.

The Schedule referred to in these Letters Patent and making part of the same.

TO ALL WHOM IT MAY CONCERN:

Be it known that I, HIRAM B. MORRISON, of Le Roy, in the county of Genesee, and State of New York, have invented a certain new and useful Improvement in Nozzles for Hose and Water-Discharge Pipes; and I do hereby declare that the following is a full and exact description thereof, reference being had to the accompanying drawings, making part of this specification.

Figure 1 is a longitudinal section of my improved nozzle.

Figure 2, a cross-section, in plane of line $x x$, fig. 1.

Figure 3, a perspective view of one of the spiral wings.

Like letters of reference indicate corresponding parts in all the figures.

I obtained Letters Patent, dated October 14, 1862, No. 36,688, and August 25, 1863, No. 39,700, for improvements in nozzles for hose and water-discharge pipes, the general features of which are embodied in my present improvement.

This invention consists in the employment of spiral wings, situated inside the water-passage, for the purpose of imparting to the jointed tip a rotary motion; the said wings being capable of being adjusted to different positions, to regulate the motion of the nozzle to distribute the water, and turning back out of the way when not required for use.

The invention further consists in the special arrangement of parts as hereinafter set forth.

In the drawings, A represents the sleeve, to which the hose is attached; B, the thimble, fitting inside of the sleeve, and screwing in the end of sleeve C, in such a manner as to form a swivel-joint; and D is the tip, which is jointed obliquely to the nozzle at b. This arrangement is similar to my patented inventions above referred to.

The spiral wings F F, which turn across the water-passage, are provided at one end with straight bearings, c c and at the opposite end with right-angled bearings, d d, which rest in corresponding recesses e f, formed in sleeve C. The wings are secured in place by means of screws g h, resting inside the bearings c d, when screwed together.

The arms i of bearings d extend through openings o o in sleeve C, their ends resting in sockets k k in the adjustable turning-ring l. This ring l rests against shoulder m, and is secured in place by nut n, which is screwed on the end of sleeve C, up against the adjustable ring, and held in position by set-screw r. The ring l is provided with offsets t t, to prevent the hand from slipping when being adjusted. v v v indicate the several packings necessary in closing the joints.

The operation will be readily understood. The water, in passing through the nozzle, strikes the spiral wings F F, (set across the passage,) and acts upon them in a manner similar to water on a water-wheel, imparting to the whole nozzle a revolving motion in sleeve A, and distributing the water from tip D in a circle.

By simply turning the ring l, I am enabled to adjust the turning-motion of the nozzle exactly as desired, whether the pressure be great or small. If it is great, the wings are set but a little way out, and if small, they may be set square across to receive the greatest impetus; or, when not required for use, they may be turned back into recesses s s, (shown in dotted lines, fig. 2,) entirely out of the way. This adjustment is of very great importance.

By the employment of this arrangement, I am enabled to give a positive rotary motion to a nozzle having but a single tip, an effect that cannot be accomplished properly by the angular nozzle alone. By inserting the nozzle through a hole in the wall, the rotary motion will deluge every part of a room, without opening the doors or windows to increase the fire.

The arrangement of the tightening-nut n, in connection with the adjusting-ring l, is of importance in holding the wings in position against the varying pressure of the water.

Under very heavy pressure, the tendency of the wings is to close, which is remedied by simply tightening up nut n.

What I claim as my invention, and desire to secure by Letters Patent, is—

1. The arrangement, inside the bent nozzle D, of the spiral wings F F, adjustable to different positions across the water-way, and capable of being fixed in place, and operating to impart a rotary motion to the nozzle by the current passing through, in the manner and for the purpose specified.
2. The arrangement, in connection with the spiral wings F, of the elbow-arms d i, resting in the turning-ring l, which is tightened in position by nut n, the whole as herein set forth.

In witness whereof, I have hereunto signed my name in the presence of two subscribing witnesses.

H. B. MORRISON.
